Des. 204,967
Patented May 31, 1966

204,967

EXPANSIBLE SEAL FOR USE BETWEEN AIRCRAFT PARTS OR SIMILAR ARTICLE

William B. Wallace, Dighton, Mass., assignor to Haveg
Industries, Inc., Wilmington, Del., a corporation of
Delaware

Filed Aug. 17, 1964, Ser. No. 81,317

Term of patent 14 years

(Cl. D71—1)

Fig. 4.

Fig. 5.

Fig. 3.

FIGURE 1 is a top plan view of my new expandible seal design;

FIGURE 2 is an elevation view of the expandible seal showing both chambers thereof expanded;

FIGURE 3 is a cross-sectional view taken along line 3-3 of FIGURE 1;

FIGURE 4 is an elevation view of the expandible seal similar to FIGURE 2 showing one chamber thereof expanded and the other chamber thereof collapsed; and

FIGURE 5 is an elevation view of the expandible seal similar to FIGURES 2 and 4 showing both chambers thereof collapsed.

I claim:

The ornamental design for an expandible seal for use between aircraft parts or similar article, substantially as shown and described.
